UNITED STATES PATENT OFFICE.

JAMES A. STOWELL, OF LEOMINSTER, MASSACHUSETTS.

POLISHING-MACHINE.

No. 811,454.

Specification of Letters Patent.

Patented Jan. 30, 1906.

Application filed March 16, 1905. Serial No. 250,381.

To all whom it may concern:

Be it known that I, JAMES A. STOWELL, a citizen of the United States, residing at Leominster, in the county of Worcester and State of Massachusetts, have invented certain new and useful Improvements in Polishing-Machines; and I do hereby declare the following to be a full, clear, and exact description of the invention, such as will enable others skilled in the art to which it appertains to make and use the same.

This invention relates to machines for polishing hair-pins and other similar articles; and it consists in the novel construction and combination of the parts hereinafter fully described and claimed.

In the drawings, Figure 1 is a front view of the polishing-machine. Fig. 2 is a plan view of the polishing-machine. Fig. 3 is an end view of the two polishing-wheels, showing their shafts and the carrier for the hair-pins in section.

A is a supporting-frame which is of any approved construction.

B and C are two polishing wheels or buffs which are formed of any approved soft material, such as cloth. These polishing-wheels are cylindrical in form and are journaled side by side in the frame and provided with means for revolving them in opposite directions, as indicated by the arrows in Fig. 3.

The wheel B is mounted on the shaft b, which is provided with a driving-pulley b'. The wheel C is mounted on a shaft c, which is provided with a driving-pulley c'. The said shafts are journaled in bearings D, which are provided with any approved means for adjusting them, so that the polishing-wheels are pressed together with any desired pressure. E represents hand-wheels for adjusting the position of the said bearings.

F is a carrier for the hair-pins. This carrier consists of an endless band of flexible material, such as a leather belt or a drive-chain, and it is arranged to work in a horizontal plane. G is the driving-pulley for the said carrier, and g represents guide-pulleys over which the said carrier passes. These pulleys are all mounted on vertical shafts or spindles carried by the said frame.

A worm-wheel H is secured on the shaft h of the driving-pulley G, and H' is a worm which gears into the said worm-wheel. The worm H' is secured on a shaft h', which is journaled in the frame A and provided with a driving-pulley I.

One portion i of the carrier is arranged in a straight line over the adjacent surfaces of the cylindrical polishing-wheels and parallel with their axes. The carrier is provided with a series of hooks J, and the hair-pins or other similar objects are suspended from these hooks and are traversed between the two polishing-wheels. The hair-pins are polished by contact with the said wheels.

K is an adjustable knock-off plate for the pins. This plate is secured to the frame in an inclined position and has its front end portion k curved crosswise of the carrier and arranged under it. The hair-pins strike this plate and are knocked off the supporting-hooks. The knock-off plate may be raised or lowered on the frame to suit hair-pins of different length.

What I claim is—

1. In a polishing-machine, the combination, with a pair of cylindrical polishing-wheels having their axes arranged in a horizontal plane, and means for revolving the said wheels; of an endless carrier having a straight portion arranged edgewise over the adjacent surfaces of the said wheels and sliding in a horizontal plane parallel with the axes of the said wheels, and means for supporting and driving the said carrier.

2. In a polishing-machine, the combination, with a pair of cylindrical polishing-wheels having their axes arranged in a horizontal plane, and means for revolving the said wheels; of an endless carrier having a straight portion arranged edgewise over the adjacent surfaces of the said wheels and sliding in a horizontal plane parallel with the axes of the said wheels, means for supporting and driving the said carrier, and a series of supporting-hooks secured crosswise of the said carrier and projecting below its bottom edge.

3. In a polishing-machine, the combination, with an endless carrier for supporting the articles to be polished, and a series of supporting-hooks secured to the said carrier; of means for supporting and driving the said carrier, and a knock-off plate for the articles having one end portion curved and arranged crosswise under the said carrier.

In testimony whereof I have affixed my signature in the presence of two witnesses.

JAMES A. STOWELL.

Witnesses:

HENRY S. DOW,

WM. A. PUTNAM.
